UNITED STATES PATENT OFFICE.

GUST CARLSON, OF SPOKANE, WASHINGTON.

AUTOMATIC CATTLE-GUARD.

1,202,268.

Specification of Letters Patent.

Patented Oct. 24, 1916.

Application filed February 25, 1916. Serial No. 80,504.

To all whom it may concern:

Be it known that I, GUST CARLSON, a citizen of the United States, residing at Spokane, in the county of Spokane and State of 5 Washington, have invented certain new and useful Improvements in Automatic Cattle-Guards, of which the following is a specification.

An object of my invention is to provide a 10 cattle guard which is so arranged that it may be mounted adjacent a railroad track and at the sides of a road or pathway and which will interpose bars or a gate across the track to prevent the trespass of cattle or 15 other animals onto the right of way or track of the railroad when the animals walk or step upon tread pieces mounted between the ties on that side of the guard structure adjacent the road or pathway.

20 A further object is to so construct and mount the parts that in normal conditions no part of the guard structure is closely adjacent to the rails or is permitted to project over or upon the trackway proper and also 25 to provide means by which the parts will be almost instantly returned to the inoperative relation as the animal moves from the operating tread and the weight thereupon is released.

30 With the above and other objects in view, my invention consists in certain novel features of construction and combinations of parts which will be hereinafter set forth in connection with the accompanying drawings 35 and then pointed out in the claims.

In the drawings:—Figure 1 is a view in perspective of a section of the trackway with my invention mounted in an operative relation. Fig. 2 is a view in front elevation of 40 the structure with the tread piece shown in the depressed position and with the parts consequently moved to the operative relation. Fig. 3 is a transverse sectional view to better illustrate the mounting and operating 45 parts.

In the mounting of my improved cattle guard, it is preferable that certain of the ties by which the rails 1 and 2 of the road are supported, and which ties are here designated as 3, 4, and 5, to be made of a greater 50 length than the ordinary supporting ties 6, which are mounted in the road bed, it being a purpose that these ties 3, 4, and 5 shall present a projecting end at each side of the 55 track, which projecting ends shall act as a

supporting structure for the mechanism to be hereinafter set forth.

A pair of supporting frame members 7 and 8 are mounted on the projecting ends of the ties 3 and 4 at spaced apart points and 60 at one side of the rails forming the track, and a pair of similar supporting members 9 and 10 are mounted at the opposite side of the track in a similar relation on the remaining projecting ends of the ties 3 and 4. The 65 supporting frame members 7, 8, 9, and 10 are substantially duplicates, and these frame members comprise the upright supports 11 and 12 which are connected across their upper ends by a continuation of the metal and 70 have the yoke portions 13 formed in this connecting portion. It is preferable that these supporting frame members be constructed of cylindrical bar or tube metal bent to the proper shape, and a mounting on the ties 3 75 and 4 may be accomplished by means of the socket members 14, or in any other desired manner, the essential point of the mounting being that the supporting frame members must be held in a substantially rigid rela- 80 tion.

Gate members 15 and 16 are constructed to comprise the upper bars 17 and 18 and the lower bars 19 and 20. The gate member 15 is supported by having the top bar 17 thereof 85 received and cradled in the yokes 13 of the supporting frame members 7 and 8, and the gate member 16 has the top bar 18 mounted within the yoke portion 13 of the supporting frame members 9 and 10, the mounting of 90 these two gate members being such that the sliding movement of the same is permitted to cause the inner end thereof to be extended across the trackway or to be withdrawn from a position of projection over or beyond the 95 rails 1 and 2 of the track. As is better illustrated in Fig. 2, the gate member 15 has the lower bar 19 thereof shaped to provide the inner shoulder 21 and an outer shoulder 22, and the lower bar 20 of the gate member 16 is 100 shaped in a like manner to provide the inner shoulder 23 and an outer shoulder 24.

A gate extending member 25 is mounted in the bearing 26 at a point adjacent the mounting of the supporting frame member 8 to be 105 capable of swinging movement and is shaped to fit around the lower bar 19 of the gate member 15 against the formation of the shoulder 22, and the withdrawing member 27 is mounted in the bearing 28 adjacent the 110

mounting of the supporting frame member 7 and is shaped as at 29 to receive the lower bar 19 adjacent the formation of the shoulder 21. On the opposite side of the track, 5 the gate extending member 30 is mounted in the bearing 31 on the ties 3 and 4 adjacent the supporting frame member 10, in a relation to engage with the shoulder 24, and a gate withdrawing member 32 is mounted in 10 the bearings 33 in a relation to engage with the shoulder 23.

The gate extending or closing members 25 and 30 are provided with the crank operating arms 34 and 35 and the gate withdrawing or opening members 27 and 32 and the crank arm extensions 36 and 37 thereof disposed to lie at right angles to the main extent of the uprights of these members, the crank arm portions being extended across in 20 the crank rods 39 and 40 which terminate at their ends in the crank arms 41 and 42 disposed in the same relation as and corresponding to the crank arms 36 and 37, these latter crank arms being mounted in the bearings 43 and 44 provided on the extended end of the tie 5.

Operating arms 45 and 46 are connected with the crank arms 36 and 37 and links 47 and 48 establish an operating connection between the operating arm 45 and the crank arm 34 and between the operating arm 46 and the crank arm 35.

The spring retaining members 49 and 50 are mounted on the tie 4 and have the free 35 ends thereof looped to be received around one of the upright bars of the members 27 and 32, these spring retaining members being adapted to normally hold the members 27 and 32 in a relation that the bearing portions 21 and 23 are engaged thereby, and the gate members 15 and 16 are held in the inoperative or open position. A plurality of tread bars 51 are disposed across beneath the rails 1 and 2, these tread bars being preferably placed parallel with the extent of the ties and spaced perhaps from one and one-half to two and one-half inches apart so that as an animal walking on the track on that side adjacent the road or pathway 45 comes into proximity to the mounting of the supporting frame members, the feet will engage with these tread members. The tread members 51 have the elongated slotted openings 52 at the ends thereof and the bars 39 and 40 are received through these elongated slotted openings so that as the animal may step upon one or several of the said bars 51, the depressing of the same will cause the parts to be swung to the relation shown 55 in Fig. 2 where the gate bars are extended across the track to close access to the right of way of the railroad. As the animal again moves from the tread bars, the spring members 49 and 50 will restore the parts to 60 the relation shown in Fig. 1 and the track 65

is then free. To make the bars 17 and 18 and also the bars 19 and 20 more secure, an eye 53 is formed on the end of the bar 18 to which the free end of the bar 17 fits as the gate members are closed, and a similar eye member 54 is formed on the end of the bar 19 to receive the free end of the bar 20.

While I have herein shown and described only one specific form of my invention, it will be understood that variations might be resorted to in the manner of supporting and mounting the structure, in the formation and construction of the tread bars, and in the construction and arrangement of other of the parts without departing from the spirit and scope of the invention, and hence I do not wish to be limited to the exact disclosure except for such points as may be set forth in the claims.

I claim:

1. An automatic cattle guard comprising a pair of supporting frame members mounted in a spaced relation and in alinement on each side of a track, a gate member supported and carried by each pair of supporting frame members and arranged to be capable of endwise movement to a position of closing across the track, springs mounted to bear against said gate members and by which the gates are normally slid endwise to be held in an open relation, and tread members arranged and connected to actuate said gate members to move the same against the action of the springs to a position of extension above the track.

2. An automatic cattle guard comprising supporting frame members mounted at each side of a track, gate members carried by said supporting frame members and consisting of a pair of bars, one of which is provided with shoulders, means engaging with one of the shoulders of each of said gate members to hold the same in an inoperative relation, and means to be engaged against the remaining shoulder of each of the gate members as an animal trespasses on the track adjacent the mounting of the guards to cause the gate to be moved to a position of extension across the track.

3. An automatic cattle guard comprising supporting frame members mounted on each side of a track, gates comprising upper and lower bars mounted in said supporting frame members to be capable of sliding movement into and out of operative relation and the lower bar of each of said gates provided with a pair of shoulders, and means arranged at each side of the track to engage with one of said shoulders to move the gates to an operative position.

4. An automatic cattle guard comprising supporting frame members mounted on each side of a track, gates comprising upper and lower bars mounted in said supporting frame members to be capable of sliding

movement into and out of operative relation and the lower bar of each of said gates provided with a pair of shoulders, means arranged at each side of the track to engage 5 with one of said shoulders to move the gates to an operative position, and means engaged with the remaining shoulder of each of the gate members to normally hold the same in an inoperative position.

10 5. An automatic cattle guard comprising supporting frame members mounted on each side of a track, gates comprising upper and lower bars mounted in said supporting frame members to be capable of sliding 15 movement into and out of operative relation and the lower bar of each of said gates provided with a pair of shoulders, means arranged at each side of the track to engage

with one of said shoulders to move the gates to an operative position, means engaged 20 with the remaining shoulder of each of the gate members to normally hold the same in an inoperative position, tread members mounted adjacent the track to be depressed by an animal trespassing thereon, and a 25 connection from said tread members to the gate closing means to cause the same to be actuated as the animal trespasses upon the track.

In testimony whereof I affix my signature 30 in presence of two witnesses.

GUST CARLSON.
